UNITED STATES PATENT OFFICE.

FRANK H. PIERCE, OF BROOKLYN, NEW YORK.

DESIGN FOR A SAWING-TABLE.

SPECIFICATION forming part of Design No. 35,004, dated August 27, 1901.

Application filed June 13, 1901. Serial No. 64,463. Term of patent 7 years.

To all whom it may concern:

Be it known that I, FRANK H. PIERCE, a citizen of the United States, residing at Brooklyn, in the county of Kings and State of New York, have invented and produced a new and original Design for Sawing-Tables, of which the following is a specification, reference being had to the accompanying drawings, forming part thereof.

10 Figure 1 is a side elevation of a sawing-table, showing my new design. Fig. 2 is a front elevation, and Fig. 3 a plan view thereof.

Like numerals of reference wherever they occur indicate corresponding parts in all the 15 figures.

As shown in the drawings, the leading or material features of my design consist of the

vertical piece or portion 1, having a longitudinal slot 2 therein, and the horizontal top portion 3, projecting from the part, piece, or 20 portion 1 at right angles thereto and having a slot 4 therein at one side thereof. 5 is a bracket at the junction of the portions 1 and 3.

Having described my invention, what I claim as new, and desire to secure by Letters 25 Patent, is—

The design for a sawing-table, as herein shown and described.

Signed by me at Brooklyn, New York, this 24th day of May, 1901.

FRANK H. PIERCE.

Witnesses:

LOUIS F. BRAUN,
A. M. PIERCE.
